His Attorney.

UNITED STATES PATENT OFFICE.

CHESTER I. HALL, OF FORT WAYNE, INDIANA, ASSIGNOR TO GENERAL ELECTRIC COMPANY, A CORPORATION OF NEW YORK.

CONSTANT-SPEED MOTOR.

Specification of Letters Patent.

Patented Aug. 9, 1921.

1,386,861.

Application filed January 28, 1920. Serial No. 354,532.

To all whom it may concern:

Be it known that I, CHESTER I. HALL, a citizen of the United States, residing at Fort Wayne, county of Allen, State of Indiana, have invented certain new and useful Improvements in Constant-Speed Motors, of which the following is a specification.

This invention relates to constant speed motors designed to operate at substantially uniform speed irrespective of the variation of operating characteristics within certain limits.

The object of my invention is to make the speed of the motor substantially constant irrespective of variations both of voltage and frequency. My motor can, therefore, be advantageously used on ordinary commercial circuits where there usually are slight but comparatively frequent variations both of frequency and voltage. My motor finds application in certain well known types of electrical demand apparatus in which a time-keeping device is necessary to determine the equal intervals of time during which the demand is measured, or to determine the times during which equal energy intervals are consumed. When so applied, my motor replaces the ordinary spring actuated clock-work. From this aspect, my motor is adapted to perform the same function as that described in a patent granted to me July 24, 1917, numbered 1,284,465.

In my former patent mentioned above, the motor is so arranged that even for a comparatively large variation in voltage, there is no perceptible variation in speed, but a variation in frequency would produce a large variation in speed. In my present invention, I provide a construction which gives from .2 to .7 per cent. error in speed upon a variation of frequency from 55 to 65 cycles.

In the embodiment of my invention herein illustrated and described, I provide a magnetic structure substantially like that described in my former patent. The oppositely positioned pole pieces may also be arranged in general like those shown in that patent. The energizing coils carried by the magnetic member are so located as to distribute the lines of force properly for the purpose of assisting in the elimination of speed variation when the frequency varies between comparatively narrow limits. The shading coil torque is made adjustable by making the

poles relatively rotatable with respect to the magnetized member. To provide automatic temperature compensation, a bimetallic thermostatic element may be operatively associated with one of the two poles in a manner similar to that shown in my previous patent.

For a more complete understanding of my invention, I provide the following description taken in connection with the accompanying drawing, in which:

Figure 1 is a diagrammatic view in perspective of an electric motor embodying my invention operatively connected to a circuit closer for closing an electric circuit at equal time intervals, and Fig. 2 is a perspective view of one of the pole pieces and its shading coil.

The motor comprises a U-shaped magnetic member 5, upon each leg of which is mounted an electric current carrying coil 6. The coils 6 are shown as connected in series with each other, and are supplied with current from the conductors 7 of an alternating current circuit. The coils 6 are, furthermore, adjustable, so that the disposition and amount of the leakage flux from limb to limb of the magnetic member 5 may be properly controlled. The magnetic member 5 carries at its ends two pole pieces 8 and 9 separated from each other by a small uniform air gap. Each pole piece carries a shading coil such as a short-circuited copper conductor 10. Each pole piece may also be independently adjusted, as, for example, by rotation about a pin 11 secured to the pole piece and inserted in a suitable aperture in the U-shaped magnetic member 5. The lower pole piece 8 may be adjusted and secured in its adjusted position independently of the other pole piece 9, which is adapted to be rotated in response to temperature changes, so that such changes may not affect the speed of the motor. The means for accomplishing the rotation of the pole piece 9 in response to temperature changes comprises a duplex or bimetallic thermostatic member 12 secured to the pole piece, and loosely positioned at its free end in a groove 18 of a stud 19 secured to member 5. The operation and construction of this bimetallic member are identical with that disclosed in my former patent, and it is deemed unnecessary here further to describe this feature, except to state that, upon an increase of the surrounding at-

mospheric temperature, the pole piece 9 is rotated so as to increase the effective torque due to this pole piece.

A metallic disk armature 13 of conducting material, such as copper or aluminum, is secured to a pivotally mounted shaft 14, and is positioned to rotate in the air gap between the poles 8 and 9 of the U-shaped magnetic member. The disk is furthermore subjected 10 to the leakage flux between the two legs of the magnetic member. The short-circuited conductors 10 are so positioned and adjusted 15 that the proper amount of torque is exerted by the pole pieces. The rotatable shaft 14 is shown as arranged to drive a mechanism 15 for causing contacts 16 in a circuit 17 to be momentarily connected at equal intervals. The mechanism 15 here shown is the same as that described in my 20 former patent referred to above.

In general, it may be stated that proper positioning of coils 6, so as to control the leakage flux, and of the pole pieces 8 and 9, results in substantially uniform speed irrespective of both voltage and frequency variation. To understand how this takes place, it is necessary to remember that the actual useful load which comprises the driving of the mechanism 15 is so slight as to be negligible. Furthermore the disk, due to the very heavy artificial load imposed by the electromagnetic drag, rotates at a very slow rate and may be considered to be practically at standstill. To secure uniform speed it is merely necessary to balance the damping load against the shading coil torque, so that the two in conjunction may produce almost standstill conditions. Upon an increase of frequency, the effective torque is varied both 40 by the increased phase displacement due to the shading coil and by the change in total flux due to the change in impedance. This would result in a change in speed were it not for the fact that the damping effect of the 45 main flux is proportionately varied so as to maintain a constant relation between the forward torque and the damping, and therefore the speed is maintained constant. The adjustment of coil 6 is effected manually and 50 is done in small steps, until from actual trial it is found that the speed becomes constant for both values of frequency corresponding to the limits of its variation.

It is to be noted that not only is frequency variation taken care of, but variations in the impressed E. M. F. are also accurately compensated for. This is brought about in exactly the same manner as in the patent referred to above.

50 I have made the explanation of my device free from abstruse theoretical calculations, mainly because such calculations would have to be based on more or less justifiable assumptions. Suffice it to say that I provide means whereby the damping load and

the forward torque may be so controlled as to bring about constant speed conditions irrespective of frequency and voltage variations within specified limits.

While I have shown in the accompanying drawings the preferred embodiment of my device, my invention is not limited thereto, and I aim in the appended claims to embrace all modifications falling fairly within the scope of my invention.

What I claim as new and desire to secure by Letters Patent of the United States, is,—

1. In a constant speed motor adapted to be connected to a source of variable frequency, a rotatable member, means for creating a torque in one direction therein that is a function of the frequency of the current supplied thereto and adjustable means for creating a torque in the opposite direction that is a dissimilar function of the frequency, said latter means being so adjusted that the torque created thereby has substantially constant relation to the first mentioned torque for a relatively large frequency variation.

90 2. In a constant speed motor adapted to be connected to a source of variable frequency, a rotatable disk armature, a magnetic member having portions disposed over the faces of said armature, a pair of pole pieces carried thereby between which said armature is disposed, and adapted to create a torque therein in one direction, and an energizing coil for said magnetic member, said coil being adjustable so as to cause such 100 in a distribution of the magnetic lines of force across the armature that an electromagnetic drag is produced therein substantially equal to the torque produced by the pole pieces for a comparatively large frequency variation.

105 3. In a constant speed motor, a rotatable disk armature, a U-shaped magnetic member having its legs disposed over the faces of said armature, a pair of pole pieces carried by said member, a shading coil for each pole piece, so arranged as to create a torque within the armature, an energizing coil for said magnetic member carried by one of the legs thereof, said coil being adjustable so 110 as to cause such a distribution of the magnetic lines crossing the armature that the electromagnetic drag therein is substantially equal to the torque produced by the pole pieces for a comparatively large frequency variation.

115 4. In a constant speed motor, a rotatable disk armature, a U-shaped magnetic member having its legs disposed over the faces of said armature, a pair of adjustable pole 120 pieces carried by said member, a shading coil for each pole piece, means for adjusting one of said pole pieces in response to temperature variation, an energizing coil carried by each of the legs of the magnetic 125 member.

member, said coil being adjustable so as to cause such a distribution of the magnetic lines crossing the armature that the electromagnetic drag therein is substantially equal to the torque produced by the pole pieces for a comparatively large frequency variation.

5. The method of producing substantially constant speed in an electric motor irrespective of frequency variations which consists in creating a torque in one direction that is

a certain function of the frequency of the source of supply, and producing an opposing torque that is a dissimilar function of the frequency, of an amount bearing a substantially constant relation to the first mentioned torque, for a relatively large variation in frequency. 15

In witness whereof, I have hereunto set my hand this 21 day of January, 1920.

CHESTER I. HALL.
